Specification of Letters Patent.

Patented May 14, 1918.

Application filed July 19, 1915. Serial No. 40,564.

To all whom it may concern:

Be it known that we, GEORGE E. MOLYNEUX and GEORGE S. GATCHELL, citizens of the United States, residing, respectively, at Bayonne, in the county of Hudson and State of New Jersey, and Roselle Park, in the county of Union and State of New Jersey, have invented certain new and useful Improvements in Multiple-Needle Sewing-Machines, of which the following is a specification, reference being had therein to the accompanying drawings.

This invention relates to improvements in multiple needle sewing machines and it has for its object to provide a machine especially adapted for uniting the abutted edges of cut knit goods pieces in one operation, the seam being that illustrated in the patent to Munsing, No. 506,524, of October 10, 1893, an additional needle being added, in the present instance, to form an additional row of stitches, the needles and looper coacting in the same manner as those shown and described in the aforesaid patent.

In the employment of a single looper in conjunction with the multiple needles when running at high speed the needle-loops present a problem in that there is a tendency in a three-needle machine of the third and sometimes the second needle-loop to deflect out of the path of the looper, causing these machines to sometimes skip stitches. This difficulty increases with the addition of one or more needles to such an extent that the problem of overcoming the detrimental tendency above referred to becomes vital to such an increase in the number of needles. In producing a seam by a multiple needle single-looper machine, the looper-loop is projected through the loops thrown out by the needles and when the needles descend they pass down beside their respective previously formed loops and into the looper-loop. As the needles continue their down-stroke they tend to draw up or contract the previously formed needle-loops shed by the looper, but owing to the fact that one limb of the looper-loop is detained by the descending needles the contracting needle-loops tend to draw the detained limb of the looper-loop into a zig-zag course causing it to reeve around the needles and through the needle-loops as the

latter are being drawn up. With an increase in the number of needles it becomes more and more difficult to fully draw up the 55 needle-loops and produce a slightly and properly formed seam by means of thread-controlling mechanisms heretofore known. While subsequent to the machine of the aforesaid patent several four-needle machines were originated for seaming the abutted edges of knit garments in one operation, the originators of these later machines avoided the problem overcome by the present improvements and employed multiple loopers. Multiple looper mechanisms are disadvantageous because they require unnecessarily large amounts of thread and the seams produced are objectionable because of the ridge, in each case, formed by superposed 60 loopers at the center line. The present improvements provide effective means for variably controlling the four needle-loops, so that immediately prior to being seized by the looper each loop is reduced to 65 a predetermined size, it having been robbed of excessive thread during its process of formation, for maintaining the needle-loops snugly about the looper during its receding movement, so that the needle-loops will remain evenly spaced apart and assume positions each at one side of its respective descending needle, and for quickly taking up the needle-loops in succession as they are shed from the looper, whereby excessive reeling of the looper-thread about the needles and needle-loops is avoided and whereby the needle-loops may be readily and fully taken up without subjecting the needle-threads to excessive strains. The details of the improvements will be understood by reference to the accompanying drawings, in which Figure 1 is a side sectional elevation of a sewing machine embodying the first form of the improvements, and Figs. 2, 3 and 4 80 are detail perspective views of the latter illustrating the manner of their operation. Fig. 5 is a front elevation of a sewing machine embodying the first form of the improvements. Fig. 6 is a side elevation of a 85 machine embodying the second form of the improvements, and Fig. 7 is a plan view of the same. Fig. 8 is a sectional plan of the machine on the line 8-8, Fig. 6. Figs.

9 and 10 are detail views, largely diagrammatic, illustrating the operation of the second form of the improvements.

The improvements are shown applied to a machine formed with the base 1, standard 2 to which is secured by screws 2^x the end flange 3 of the tubular work supporting arm 4, the standard having extended from its tubular end the overhanging tubular arm 5 terminating in the hollow head A. Journaled within and crosswise of the standard is the main-shaft 7 which is provided with the needle actuating crank 8, looper actuating eccentrics 10 and 11, feed actuating eccentric 12 and feed lift eccentric 13.

The needle-bar 14, carrying four needles, derives its operative movements from the crank 8 through the pitman 16, crank-arm 17 on the rock-shaft 18, and crank-arm 19 on said rock-shaft connected with the needle-bar by means of the link 20, in a manner well known. The looper carrier 21, carrying the looper 22, is pivotally mounted upon the looper supporting rock-shaft 23 journaled within and axially of the work-supporting arm 4 and deriving its rocking movements from the eccentric 10 through the eccentric-rod 24, plural-armed rocker 25 and link connection 26 with the crank 27 upon said rock-shaft, as shown and described more fully in Molyneux Patent No. 1,127,067, of February 2, 1915. The sidewise movements of the looper are derived from the eccentric 11 through the eccentric-rod 28 pivotally connected with the endwise-movable bar 29 journaled in the arm 4 beneath the looper-supporting rock-shaft and having a sliding and pivotal connection with the looper carrier similarly to that of the said patent. The two differentially-movable feeding members and the mechanism for actuating the same shown in the drawings, are fully described in Molyneux application filed June 5, 1915, Serial No. 32,269; and the thread carriers T and their actuating mechanism form the subject of Molyneux application filed of even date herewith.

The needle-threads are led from the source of supply to suitable tension devices indicated at t in the drawings and thence pass through apertures formed in two rigid guide-members between which a series of spring-fingers coact with the take-up arm on the needle-bar to control the needle-threads, including the sizes of the needle-loops.

In the first form of the improvements illustrated in Figs. 1 to 5 inclusive, the first rigid guide-member is the vertically disposed arm 30 formed with a depending supporting post fitted within a suitable aperture formed in the head A of the overhanging arm 5. After passing through the four horizontally disposed apertures in the arm 30, the thread is led through the similarly-ar-

ranged apertures formed in take-up arm 31 secured upon the upper end of the needle-bar 14 by means of the screw 32; the thread then passing over the cross-bar 33^x of a bracket 33, formed with a slot at 34 to receive a stud 35 tapped into the head A, as shown in Fig. 5. From the cross-bar 33^x the thread is led through a series of apertures formed in the bracket 33 in an inclined line, thence passing to the needles. 75

Secured upon a block 36 by means of the set-screws 37, and normally lying in horizontal position below the guide-arm 30 and take-up arm 31 are four spring-fingers a, b, c, d, each finger lying within a vertical 80 slot formed in a stop-plate 38 formed with an off-set depending base slotted to receive the set-screw 39 by means of which the stop-plate is adjustably secured upon the head A. The slots formed in plate 38 are of gradually 85 increasing depths, so that by the end walls of the more shallow slots the spring-fingers are stopped at a higher elevation than are those positioned in the deeper slots. The end of each finger lies intermediate the cross-bar 33^x and the inclined apertures in the bracket 33, and is apertured to receive a needle-thread for the purpose hereinafter set forth. 90

When the needle-bar reaches its highest 95 position the spring-fingers a, b, c and d are elevated above the end walls of their respective stop-slots by the pull on the threads caused by the take-up arm 31, as shown in Fig. 4. As the needle-bar descends the 100 spring-fingers take up the needle-thread and prevent the formation of slack thread between the needle-eyes and the work. As the needle-eyes double their respective threads below the work the spring-fingers are elevated and give up the thread required by the descending needles. After the needle n⁴ has entered the looper-loop the previous needle-loop is shed or released by the looper, whereupon the spring-finger a immediately drops 110 sufficiently to pull the released thread back through the eye of the needle, thereby taking up the loop previously formed by the needle n⁴. This is readily accomplished 115 since the looper-thread has not been deflected into a zigzag course by contraction of the other needle-loops. In the same manner the loops previously formed by the needles n³, n² and n¹ are shed by the looper and successively drawn up by the spring-fingers 120 b, c and d, respectively. As the needles reach their lowest position the spring fingers a, b, c, d, are elevated from their normal position in contact with the lower walls of the slots in stop-member 38, to the position shown in Fig. 2, by the action of the needles in pulling upon the threads leading to the inclined series of guide apertures in the bracket 33 and the action of the take-up arm in pulling the threads over the cross- 125 130

bar 33^x. It is obvious that as the needle-bar rises, the spring-fingers *a*, *b*, *c* and *d* take up or steal thread from the nascent needle-loops until the eye of the needle *n*¹ reaches a 5 position slightly below the path of the advancing looper. At this time the spring-finger *d* reaches the bottom of its stop-slot and the needle *n*¹, continuing to rise, throws out a thread-loop of proper size to 10 be seized by the looper. By the time the needle *n*² has reached a similar position, slightly below the looper-path, the spring-finger *c* has reached the bottom of its stop-slot and the needle *n*² presents its loop to 15 the looper. The sizes of the loops thrown out by the needles *n*³ and *n*⁴ are controlled in the same manner.

After all of the needle-loops have been seized by the looper it becomes necessary to 20 maintain them in proper position on the looper so that in the succeeding descent of the needles from the position shown in Fig. 4 they will pass to one side of their previously formed loops and will properly engage the looper-loop. To this end as the needle-bar continues to rise the take-up arm 31 reaches a point above the cross-bar 33^x at which it begins to pull upon the threads leading to the spring-fingers so that the latter are elevated until the needle-bar reaches the limit of its rise and assumes the position shown in Fig. 4. Thus the needle-loops are held snugly about the looper-blade throughout the rise of the needles, and 35 during the descent of the needles the spring-fingers descend also to maintain the needle-threads closely under control until the needles have passed down beside their previously formed loops and into the looper-loop. 40 If the needle-threads are allowed to slacken during the descent of the needle, the needle-loops about the looper will be loosened to such an extent that there is danger of their assuming non-uniformly spaced positions 45 along the looper-blade, with the result that the descending needles may not properly pass their needle-loops. If the needles are arranged close together, as is particularly desirable in a four-needle machine, it is essential 50 that the needle-threads be kept closely under control as the needles descend.

In the second form of the improvements the thread is relieved from the strain imposed upon it in elevating the spring-fingers as hereinbefore described, and such strain is thrown upon a series of cam-rollers which positively lift the fingers at the proper times and subsequently permit them to descend to their normal position.

As shown in Fig. 7, the thread controlling fingers 40-41-42-43 are pivotally mounted upon a pin 44 fitted in suitable apertures formed in the spaced upwardly-extending arms 45^x of a bracket 45 secured upon the upper face of the overhanging arm by means

of the screws 46. The arms 45^x of the bracket also serve as bearing members for a cross-shaft 47 which carries four cam-rollers 48-49-50-51, and upon the upper surface of each roller rests the bearing disk *k* 70 of the thread controlling finger which the roller actuates. Surrounding the hub *h* of each thread-controlling finger is a spring 52 which is secured at one end in a groove formed in the cross-bar 53 of bracket 45 and 75 which is hooked at its opposite end to embrace the finger. It will be understood that the series of springs 52 serve to move the fingers downwardly when the cam-rollers permit such action. 80

Fixed upon one end of the shaft 47 is a gear-wheel 54 which meshes with a gear-wheel 55 on the upper end of a shaft 56 journaled near its upper end within a bearing member 57 supported by the bracket 45 85 and journaled near its lower end within a bearing boss 58 projecting laterally from the standard. At its lower end shaft 56 carries a gear-wheel 59 which meshes with gear-wheel 60 on cross-shaft 61. 90

In the second form of the improvement the needle-threads are led from the tension devices *t* to a rigid guide-bar 62 having longitudinally arranged thread-receiving apertures, thence to the controller fingers and 95 thence to a second rigid guide-bar 63 having longitudinally arranged thread receiving apertures from which the thread pass to the take-up arm on the needle-bar.

The thread controlling fingers 40-41-42-43 act upon the thread in the same manner as those of the first form of the improvements. As shown in Fig. 9, the cam-rollers act upon the thread controlling fingers in such manner that immediately prior to the 105 forward movement of the looper to seize the needle-loops the fingers are held in elevated position, the degree of elevation of the successive fingers increasing from the finger 43 to the finger 40. As the looper moves forward, the cam-rollers permit the fingers to descend under their spring impulses, and as the fingers 42-41 and 40 have successively longer paths of movement, the needle-loops farthest away from the looper are acted 115 upon to the greater extent. If desired, the cam-roller 51 may be so formed, as not to affect the thread controlling finger 43, and hence not to disturb the first needle-loop, during the loop seizing movement of the 120 looper. After the looper has entered all of the needle-loops the cam-rollers act to raise the thread controlling fingers to the position shown in Fig. 6, and in the succeeding descent of the needles the cam-rollers 125 permit the fingers to move downwardly to pull upon the needle-loops and thereby hold them against deflection upon the looper-blade, and to successively take up the needle-loops as they are shed from the looper.

It will be understood that various changes may be made in the form and arrangement of the elements herein shown and described without departing from the scope of the invention.

Having thus set forth the nature of the invention, what we claim herein is:—

1. A sewing machine having a plurality of needles set in a plane crossing the line of feed, a single looper coöperating therewith to form stitches, thread-controlling devices adapted for differentially timed action upon the needle-threads, and thread-guides coöperating with said devices, said thread-controlling devices operating to take up substantially all of the slack thread formed during the first part of the down stroke of the needles and to successively tighten the needle-loops as they are shed from the looper.
2. A sewing machine having a plurality of needles set in a plane crossing the line of feed, a single looper crossing the line of feed and coöperating therewith to form stitches, and independently acting devices adapted to closely control the needle-threads until the needles enter the looper-loop, whereby the formation of slack thread is prevented during the first part of the down stroke of the needles, said devices being further adapted to successively tighten the needle-thread loops as they are shed from the receding looper.
3. A sewing machine having a plurality of needles set in a plane crossing the line of feed, a single looper crossing the line of feed and coöperating therewith to form stitches, and successively actuated means coöperating with said needles to tighten the needle-loops successively as they are shed from the looper.
4. A sewing machine having a plurality of needles set in a plane crossing the line of feed, a single looper coöperating therewith to form stitches, thread-controlling devices for the needle-threads, thread-guides coöperating with said devices, and means whereby said devices are caused to move relative to said thread-guides to take up all of the slack thread formed during the first part of the descent of the needles and to successively tighten the needle-loops as they are shed from the looper during the continued descent of the needles.
5. A sewing machine having a single looper and a plurality of needles set in a plane crossing the line of feed with the eyes disposed at progressively lower elevations beginning with the needle nearest the point of the advancing looper, and thread-controlling means for the needle-threads acting to steal thread in progressively lesser amounts from certain of the nascent needle-loops beginning with the last loop to be seized by the looper.
6. A sewing machine having a plurality of needles set in a plane crossing the line of feed with the eyes of the needles at different elevations, a single looper coöperating therewith to form stitches, thread-controlling means for each needle-thread, and means whereby said thread-controlling means are caused to reduce the sizes of certain of the needle-loops prior to their seizure by the looper and to successively tighten the needle-loops as they are shed from the looper.
7. A sewing machine having a plurality of needles set in a plane crossing the line of feed with the eyes of the needles at different elevations, a single looper coöperating therewith to form stitches, and means for stealing thread from certain of the nascent needle-loops and for successively pulling certain of the needle-threads back through the eyes of their respective needles to tighten the respective needle-thread loops successively as they are shed from the looper.
8. A sewing machine having a plurality of needles set in a plane crossing the line of feed, a single looper coöperating therewith to form stitches, and means for simultaneously taking up the needle-threads during the first part of the down stroke of the needles, for successively giving up thread to the needles as the eyes thereof descend below the work, and for successively tightening the needle-loops as they are shed by the looper.
9. A sewing machine having a plurality of needles, a single looper coöperating therewith to form stitches, thread-engaging devices for the needle-threads, thread-guides coöperating with said thread-engaging devices and means whereby said thread-engaging devices are caused to move relative to said thread-guides to take up all the slack below the eyes of the descending needles, thereby maintaining the previous needle-loops snugly about the looper, and to successively tighten the needle-loops as they are shed by the looper during the further descent of the needles.
10. A sewing machine having a plurality of needles set in a plane crossing the line of feed with the eyes of the needles at different elevations, a single looper coöperating therewith to form stitches, and independent thread-controlling devices for the needle-thread adapted for differentially timed actions upon their respective needle-threads to take up substantially all of the slack thread below the eyes of the descending needles, whereby the needle-threads are closely controlled during the first part of the down stroke of said needles, said devices being further adapted to give up slack thread to the needles successively as the eyes thereof descend below the work and to tighten the needle-loops successively as they are shed from the retracting looper.

11. A sewing machine having a plurality of needles set in a plane crossing the line of feed, a single looper coöperating therewith to form stitches, and thread-controlling devices for the needle-threads each constructed to act independently of the other devices to give up thread to its respective needle as the eye thereof descends below the work and to tighten its respective needle-thread loop as soon as it is shed from the retracting looper.
12. A sewing machine having a plurality of needles set in a plane crossing the line of feed, a single looper coöperating therewith to form stitches, and independently acting thread-controlling devices for closely controlling the needle-threads, each of said devices being constructed to give up thread to its respective needle as the eye thereof descends below the work and to reverse its action upon its respective needle-thread as the loop thereof is shed from the retracting looper, whereby the needle-loops are tightened successively and the formation of slack thread is prevented.
13. A sewing machine having a plurality of needles set in a plane crossing the line of feed, a single looper crossing the line of feed and coöperating therewith to form stitches, thread-guides for the needle-threads, and thread-engaging devices adapted to execute successive take-up actions relatively to said thread-guides and coöperating with said needles to tighten the needle-loops successively as they are shed from the looper.
14. In a sewing machine, the combination with stitch-forming mechanism including a plurality of reciprocating needles fixed relatively to one another, of a series of thread-engaging arms one for each needle-thread, and means for differentially moving the said thread-engaging arms for controlling the nascent needle-loops, and for controlling the slack thread during the first part of the down stroke of the needles.
15. In a sewing machine, the combination with stitch-forming mechanism including a plurality of needles and a looper, of a series of thread-controlling arms, one for each needle-thread, means for elevating the said arms into position for action during the descent of the needles, and means adapted to stop the said arms in succession in their active descent during the upstroke of the needles as the looper moves toward loop-seizing position.
16. In a sewing machine, the combination with stitch-forming mechanism including a plurality of needles, of means for effecting the differential control of the needle thread-loops, including a series of spring-pressed thread-engaging arms, and positively acting means for moving said arms, the degree of movement differing in successive arms.
17. In a sewing machine, the combination with a stitch-forming mechanism including a plurality of needles fixed relatively to one another, of a series of spring-pressed thread-engaging arms, a stop adapted to hold the said arms in relatively different positions and movable to permit said arms to assume relatively uniform position during the loop forming action of the needles.
18. In a sewing machine, the combination with stitch-forming mechanism including a plurality of needles, of a series of spring-pressed thread-engaging arms, a shaft, a series of cams on said shaft engaging the said arms, and means for actuating said shaft to impart differential movements to said arms.
19. In a sewing machine, the combination with stitch-forming mechanism including a plurality of needles, of a series of spring-pressed thread-controlling arms, each arm engaging a needle-thread, a stop member adapted to hold the said arms in relatively different heights, and means for lifting said arms to a predetermined position thereafter permitting the arms to move into engagement with the stop member and in such movement to withdraw thread from the needle-loops in amounts varying among the arms.
20. In a sewing machine, the combination with stitch-forming mechanism including a plurality of needles and a looper, of a series of thread-controlling arms, one for each needle-thread, a take-up device, means including said take-up device for elevating the said arms and for releasing the arms during the loop seizing movement of the looper, and a stop device adapted to stop the said arms in succession.
21. In a sewing machine, the combination with stitch-forming mechanism including a plurality of needles, a series of spring-pressed thread-engaging arms, a stop device normally holding said arms in relatively different positions, a thread-guide intermediate the said arms and the needles, a reciprocatory take-up arm, a thread-guide intermediate the said take-up arm and the thread-controlling arms, and means for moving the take-up arm downwardly during the descent of the needles and thereby exerting a pull upon the needle-threads to lift the thread-controlling arms out of normal position whereby during the rise of the needles the said thread-controlling arms will descend to normal position and draw successively different amounts of thread from the needle-loop.
22. In a sewing machine, the combination with stitch-forming mechanism including a plurality of reciprocating needles fixed relatively to one another in a plane crossing the line of feed, a single looper coöperating therewith to form stitches, a series of thread-engaging arms each engaging a

needle-thread, and means for differentially moving the thread-engaging arms for controlling the nascent needle-loops, said arms being adapted to impose a tension upon the 5 needle-threads during the descent of the needles through the looper-loop.

23. In a sewing machine, the combination with stitch-forming mechanism including a plurality of needles fixed relatively to one 10 another and a looper, of means for controlling the nascent needle thread-loops, comprising a series of spring-pressed arms, and means for effecting the movement of said arms to impose a tension upon the needle- 15 threads during the descent of the needles.

24. A sewing machine having a plurality of needles set in a plane crossing the line of

feed with the eyes of the needles at different elevations, a single looper coöperating therewith to form stitches, thread-guides for the 20 needle-threads, and thread-engaging devices timed to execute differential take-up actions relatively to said thread-guides to give up slack thread to the needles successively as their eyes descend below the work, to tighten 25 the needle-loops successively as they are shed from the looper, and to thereafter give up thread required by certain of the needles in completing their down-strokes.

In testimony whereof, we have signed our 30 names to this specification.

GEORGE E. MOLYNEUX.
GEORGE S. GATCHELL.
